UNITED STATES PATENT OFFICE.

JOHN FOURNIA, OF ALBANY, NEW YORK.

AUTOMATIC TRAIN-STOP.

1,177,942.

Specification of Letters Patent.

Patented Apr. 4, 1916.

Application filed June 18, 1913. Serial No. 774,324.

To all whom it may concern:

Be it known that I, JOHN FOURNIA, a citizen of the United States, residing at Albany, in the county of Albany and State of New York, have invented a certain new and useful Improvement in Automatic Train-Stops, of which the following is a specification, reference being had therein to the accompanying drawings, forming part thereof.

10 My invention relates to railway traffic-controlling devices and particularly to that class of traffic-controlling devices which are known as automatic train stops.

In my co-pending application, Serial Number 747,856, filed February 12, 1913, I have shown and described an improved automatic train stop which as operated at each signal post and which will therefore apply the brakes and stop the train at the entrance to each block unless its operation is prevented by a positive act on the part of the engineman or motorman. In addition to the operating devices at the respective signal posts, I have also shown in said prior application a device somewhat in rear of each signal post which is controlled by the signal apparatus at that post and is arranged to be operative only when the signal apparatus is energized to hold the signal at clear. In my said prior application, I have shown and described as the stationary actuating devices located at the various signal posts and in rear thereof, mechanical tripping devices constructed to protrude above the head of the rail and mechanically engage a lever carried by the railway vehicle and thus operate the automatic train stop. This form of operating device has certain disadvantages, however, and one object of 40 this invention is to provide improved tripping or actuating means for the automatic brake applying apparatus.

Other objects of my invention are simplicity and compactness of construction and reliability of operation. Still other objects and advantages of my invention will appear from the following description.

My improved tripping or actuating device comprises a movable magnetic member which is carried by the vehicle and which is related to the brake applying mechanism in such a way that its movement serves to apply the brakes and which cooperates with a stationary armature member laid in the track in position to cause the magnetic

member to move as the vehicle passes the armature.

More specifically, the magnetic member is an electro-magnet, preferably in the form of a stationary solenoid with a removable core, 60 and in order that a failure of the electro-magnet may be on the side of safety, an electro-translative device is arranged in series with the electro-magnet and is so related to the brake applying apparatus as to 65 apply the brakes when on open circuit.

The movable magnetic member is arranged in control of an operating lever for the brake applying apparatus and is adapted by its movement to move the lever to operative position. Specifically the lever has a bias to non-operative position and is preferably counterweighted with a bar of magnetic material. An armature may be disposed in each block at a safe stopping distance in rear of the signal and one or more electro-magnets may be arranged at the side of this armature, arranged to be energized when the signal actuating mechanism is energized, and these electro-magnets will act 80 upon the magnetic member which is carried by the lever and which serves as a counterweight therefor, and will counteract the tendency of the armature in the track to attract the electro-magnet on the bar when 85 the signal actuating mechanism is energized and the signal is at clear, while permitting the armature to freely attract the electro-magnet carried by the lever and apply the brakes when the signal is at danger. 90

My invention also comprises various other features and arrangements and combinations of parts as will hereinafter more fully appear.

I shall now describe the embodiment of 95 my invention illustrated in the accompanying drawings and shall thereafter point out my invention in claims.

Figure 1 is a diagrammatic representation of my brake applying apparatus as positioned upon a locomotive, a portion of the locomotive being shown in outline, with the train-carried part of the actuating or tripping mechanism in operative relation to a stationary part. Fig. 2 is a diagrammatic 100 representation, partly in sectional elevation, of the apparatus. Fig. 3 is a transverse sectional elevation of the operating valve, taken on line 3-3 of Fig. 5. Fig. 4 is a bottom detail view of the rotary valve head 105 1. 1

showing the stem in section. Figs. 5 and 6 are central longitudinal sectional elevations of the operating valve, showing the valve, respectively, in non-operating and in operating positions. Fig. 7 is a diagram showing one complete block and portions of two adjacent blocks and showing the electric circuits and the relative positions of the stationary members of the actuating mechanism, and a plan representation of the train-carried part of the actuating mechanism.

In the drawings, I have shown as much of the brake applying apparatus as is necessary for a complete understanding of the operation of my improved actuating or tripping mechanism. The illustrated apparatus, which is that shown in my said prior application, is connected with the air brake system and is operated by the air pressure used in this system. A vent 1 is provided in a branch pipe 2 of the train pipe 3 and the train pipe is vented to reduce the pressure therein and apply the brakes by operating the brake-applying valve device arranged in control of this vent 1. This brake-applying valve operates by varying the relative pressures on opposite sides of an equalizing piston valve 4 in control of the vent 1. This equalizing valve 4 is closed when the pressures on its opposite sides are substantially equal, and is raised off its seat and opens the vent when the pressure on its under side is excessive. The brake applying valve includes two chambers 5 and 6, the former of which is termed a high pressure chamber, and the latter a low pressure chamber, and communication between which is controlled by a slide valve 7 which is adapted to reciprocate in the casing 8 of the brake-applying valve. In the normal position of the slide valve 7, which is shown in Fig. 2, the chamber 5 communicates with the train pipe 3 through the branch pipe 2, passageway 9, bridging recess 10 in the slide valve 7 and passageway 11; and the chamber 6 communicates with an atmospheric port 12 through the passageway 13, and the bridging recess 14 in the slide valve 7. Communication between the main reservoir pressure line 15 and the engineer's valve 16 is provided through a conduit including the pipe 17 leading into the upper part of the casing 8 of the brake applying valve, and the pipe 18 which leads from the casing 8 to the engineer's valve 16. Main reservoir pressure is therefore provided upon the slide valve 7 which tends to hold the slide valve seated in any position to which it is moved.

With the slide valve in the position shown in Fig. 2, the pressure upon the opposite sides of the equalizing valve 4 is equal, and since the exposed area of the upper side of the valve is greater than that of the lower side, the valve is seated under these conditions and holds the vent 1 closed. When the

slide valve 7 is moved to the left, the bridging recess 10 in the slide valve is moved over so as to connect the passageways 11 and 13, and in this position of the valve, therefore, the two chambers 5 and 6 are connected while communication between the chamber 5 and the train pipe is interrupted and the communication between chamber 6 and the atmospheric port 12 is interrupted. The pressure in the chamber 5 immediately falls until the pressure in the two chambers 5 and 6 is equal, and since the pressure upon the upper side of the equalizing valve 4 is thereby reduced, this equalizing valve is raised off its seat by pressure on its under side, and the train pipe is vented until the pressure in the train pipe becomes substantially equal to that in the chambers 5 and 6, when the valve 4 is again seated and the vent closed. The amount of reduction in pressure is, of course, determined by the relative volume of the two chambers 5 and 6, and this is fixed by the desired reduction. It is apparent that when the slide valve 7 is thus operated, the equalizing valve 4 holds the vent 1 open until the pressure in the train pipe has fallen the predetermined amount, irrespective of the amount of air that must escape to effect this reduction. The brakes are applied in this manner very gradually and without any sudden jolt, or, in other words, the usual service application of the brake is thus made. When the slide valve 7 is in this brake applying position, it closes off the port connecting with the pipe 18, and thereby closes off communication between the engineer's valve 16 and the main reservoir, and thus prevents the main reservoir pressure from passing into the train pipe and keeping up the train pipe pressure to running condition when the train pipe is vented.

To thus operate the brake applying valve operating means are employed which are automatically operated by the actuating means which forms the subject of this application, and in the embodiment shown a piston device is employed which is operated by air pressure from the main reservoir line 15 and controlled by the operating means. The piston device comprises a piston 19 which reciprocates in a cylinder 20 and is connected to the slide valve 7 by a piston stem 21 and thereby transmits reciprocation to the slide valve 7. A conduit provides communication between the main pressure reservoir line 15 and the cylinder 20, and includes branches leading to opposite sides of the piston 19, and communication with these respective branches is controlled by the operating valve, which is a rotary valve and is actuated by the magnetic actuating means, as will hereinafter appear. This conduit includes the pipe 22 leading from the main reservoir pressure line 15 to the

rotary valve, and from this rotary valve lead the two branches, one the pipe 23 leading to the cylinder 20 in front of the piston 19 so that air entering from the pipe 23 will move the slide valve 7 to the position shown in Fig. 2, and the other consisting of the pipes 24 and 25 the latter of which leads behind the piston 19, and communication between which is controlled by the 10 manually actuated controlling valve hereinafter to be described.

The operating valve is a rotary valve which is shown in detail in Figs. 3, 4, 5 and 6. This rotary valve is actuated by a lever 15 arm 26 which is fixed upon the stem 27 of the valve and which normally extends down in vertical position. Fixed upon this stem is the rotary valve head 28 which rotates upon the valve seat 29. The valve seat 29 is 20 provided with two pressure passageways 30 and 31, and with an atmospheric passageway 32, and the pressure passageways 30 and 31 are connected to the pipes 23 and 24 respectively. The pipe 22 communicates 25 with the port 33 in the cap 34 of the operating valve and the main reservoir pressure enters this port 33 and envelops the rotary valve head 28 and passes out of the passageway 30 through a port 35 in the rotary 30 valve head or out of the passageway 31 according to the position of the rotary valve head 28. In the normal or vertical position of the rotary valve head, the port 35 registers with the passageway 30 as shown in 35 Fig. 5, and main reservoir pressure therefore normally passes through the pipe 23 into the cylinder 20 in front of piston 19. The rotary valve head 28 is cut on its two opposite sides as shown in Figs. 3 and 4, 40 providing a central portion which in the normal position of the rotary valve head overlies the entrance to the passageway 31 and closes this means of communication between this passageway 31 and the port 33. 45 The under-side of the rotary valve head is provided with a recess 36 which furnishes communication between the passageway 31 and the atmospheric passageway 32 in the normal position of the valve head, as shown 50 in Fig. 5. This recess 36 is provided with two radial extensions 37 on opposite sides of the port 35, and as shown in Fig. 6, these recess extensions 37 provide communication between the passageway 30 and the atmospheric passageway 32, as the rotary 55 valve is rotated. It will be noted that communication will be provided as above described when the rotary valve head is actuated, irrespective of the direction in which 60 the valve is rotated, since there are two cut-away portions and two recess extensions 37, and one of these will be brought into service when the valve is rotated in one direction and the other when the valve is rotated in 65 the opposite direction. However, with my

improved actuating mechanism hereinafter described, the valve is actuated in only one direction.

It will now be understood that in the normal or non-operating position of the operating valve, as shown in Figs. 1, 2, 3 and 5, main reservoir pressure is being admitted through the pipe 23 in front of the piston 19, while the space behind, being connected to the atmospheric passageway 32 through the pipes 25 and 24, the passage 31 and the recess 36, is at atmospheric pressure; and that when the lever arm 26 is actuated and the valve 28 is rotated, these connections are reversed, and the pipe 23 is connected with the atmospheric passageway 32, and pipes 24 and 25 are connected with the main reservoir pressure. If nothing operates to prevent communication between the pipes 24 and 25, the main reservoir pressure will 85 operate to move the piston 19 and hence the slide valve 7 to the position opposite that shown in Fig. 2 and the brakes will be applied in the manner heretofore described. To prevent the application of the brakes, 90 however, manually operated controlling means are provided under the control of the engineer by which communication between the pipes 24 and 25 is prevented, and the main reservoir pressure which is admitted 95 to the pipe 24 is diverted to effect the operation of a restoring device to restore the operating valve to its normal position, as will now be described.

Located in the cab within convenient reach 100 of the engineer is the controlling valve, which comprises a slide valve 38 reciprocative in a valve casing 39. Main reservoir pressure is admitted through the pipe 40 into the top of the casing 39, and this pressure fluid envelops the slide valve 38 and holds it seated and in the position to which it is moved. Secured to a rearwardly extending stem 41 on this slide valve is an operating handle 42 pivoted at its lower end 105 and connected with a treadle member 43 whereby the stem 41 can be reciprocated either by foot or by hand. The handle 42 is provided with a stop 44 which engages a latch 45 in the normal position of the latch, 110 as shown in Fig. 2, after the handle 42 has been moved a short distance. This latch 45 has on its lower end the piston 46 slidable in a cylinder 47, and this piston is normally held in an elevated position by a spring 48, 115 120 and is withdrawn by fluid pressure admitted to the upper side of the piston 46, as will hereafter appear.

In the normal position of the slide valve, shown in Fig. 2, a bridging passageway 49 125 provides communication between the pipes 24 and 25, but as the engineer moves the handle 42, or treadle 43, until the stop 44 engages the latch 45, he thereby moves the slide valve 38 sufficiently to connect the pipe 130

25 through a bridging passageway 67 with an atmospheric port 50 in the casing 39, and to connect the pipe 24 through the bridging passageway 49 with a pipe 51 which has two 5 branches, one branch 52 leading to the upper side of the latch piston 46, and the other branch 53 leading behind a cylinder 54 connected by a stem 55 with the slide valve 38, and reciprocative in a piston 56. The air 10 thus admitted to the pipe 51 from the pipe 24 serves both to retract the latch 45 from the path of the stop 44 and to complete the movement of the slide valve 38 by the pressure fluid admitted behind the piston 54. It 15 will therefore be seen that the engineer merely initiates the operation of the controlling valve and that thereafter its operation is automatically completed. This further 20 automatic movement of the slide valve serves to operate a restoring device for the operating valve to restore the apparatus to its normal running condition, and also to admit pressure fluid in front of the piston 54 to restore the control valve to its normal position, as will now be described.

The restoring device is located directly above the operating valve and both are carried inside the drive wheels upon a plate 82 secured at its ends to the boxes 83 of the 30 drive wheels of the locomotive. Being thus carried by the same member, the relative distance between the two is always the same, and, since they are both supported upon the axles of the locomotive, the relative distance 35 between the lever arm 26 and the rail is always the same, there being no spring to yield and vary this relative distance. It will be readily understood that it is desirable to keep this relative distance constant, in order that the distance between 40 the magnet and armatures of the actuating mechanism for the operating valve may be constant. Since the other parts of the apparatus are mounted upon the spring supported superstructure of the locomotive, it 45 is essential to provide flexibility in the pipe connections between the yielding and the rigid parts of the apparatus, and this may be provided in any suitable way, as by flexible pipe sections, as shown in Fig. 1.

The restoring device comprises two diverging arms forming an inverted V-shaped device 57 disposed directly above the upper end of the lever 26 carried upon the downwardly extending stem 58 on a vertically sliding piston 59 which reciprocates in a cylinder 60. This piston 59 and connected parts are normally maintained in elevated position by a spring 61, and by air pressure 55 which enters through a pipe 62 which enters the cylinder 60 on the under side of the piston 59, and communicates with the port in the casing 39 of the controlling valve with which a transverse slot 63 in the slide valve 60 65 38 normally registers. Main reservoir pres-

sure which envelops the slide valve 38 normally passes through this slot 63 and thence through the pipe 62 to the under side of the piston 59 and supplements the spring 61.

To depress the piston 59 and restore the operating valve, fluid pressure is admitted upon the upper side of the piston 59 through the pipe 64 and under the control of the controlling slide valve 38. This pipe 64, in the normal position of the slide valve, 70 communicates with a longitudinal passageway 65 in the slide valve which communicates with the atmospheric port 50 as long as the slide valve is in such position that the passageway 65 communicates with the pipe 64. 75 It is therefore apparent that in the normal condition of the apparatus, the space above the piston 59 is vented to the atmosphere. After the movement of the slide valve 38 has been manually initiated and the pressure fluid from the pipe 24 diverted into the pipe 51, the movement of the slide valve 38 is completed by the pressure fluid entering into the pipe 53 behind the piston 54, in the manner above described. This further 80 movement of the slide valve 38 brings the slot 63 into register with the port leading to the pipe 64 and pressure fluid from the pipe 40 is thereby admitted through the pipe 64 above the piston 59. At the same time 85 the port leading to the pipe 62 is brought into communication with a bridging recess 66 on the underside of the slide valve 38, which communicates through a port on its upper side with the passageway 65, and is thereby vented to the atmosphere through the atmospheric port 50, the bridging recess 67 at the end of the passageway 65 being of such length that the passageway 65 is in 90 communication with the atmospheric port 50 throughout the entire range of movement of the slide valve 38. Since pressure fluid is admitted to the upper side of the piston 59 and the space below the piston 59 is at the same time vented to the 95 atmosphere through the connection described, the restoring device is depressed, and the lever arm 26 is restored to its vertical position by the V-shaped member 57, and the operating valve is restored to its 100 normal position. The pipe 24 is thereby 105 again connected with the atmospheric passageway 32 in the operating valve, and hence the space behind the piston 54 and the space above the piston 46 are vented to 110 the atmosphere, and the operating valve is 115 ready to be restored to its normal position through the means now to be described.

A conduit connects the cylinder 56 in front of the piston 54 with the pipe 22, and 120 the valve in this conduit is controlled by the final movement of the restoring mechanism. The piston 59 is provided with an upwardly extending stem 68 which projects into the cylinder 69 and is slotted as shown in Fig. 2, 125 130

and a pin 84 on a slide valve 70 in the cylinder 69 engages in this slot. This slide valve 70 is provided with a bridging recess 71 which, in the normal position of the slide valve, provides communication between an atmospheric port 72 and a port leading to a pipe 73 which leads to the cylinder 56 and which forms one part of the conduit providing communication between the pipe 22 and the cylinder 56, while the pipe 74 which connects the cylinder 69 with the pipe 22 forms the other part of the conduit. The main reservoir pressure continually enters this cylinder 69 through this pipe 74 and 10 develops the slide valve 70 and maintains this slide valve upon its seat and holds it in adjusted position. It will be noted that the space in front of the piston 54 is normally vented to the atmosphere through the pipe 73, recess 71 and atmospheric port 72, so that the piston 54 and the slide valve 38 connected thereto are free to be moved to the right as above described. After the restoring device has been depressed, however, sufficiently to restore the operating valve, the 20 upper end of the slot in the stem 68 engages the pin on the slide valve 70 and the fluid pressure entering through the pipe 64 continues to depress the restoring device, this continued movement being permitted by a slot 75 formed at the top of the restoring member at the juncture of the two diverging arms as shown. The further downward movement of the restoring device serves to 30 move the slide valve 70 down until communication is provided between the cylinder 69 and the pipe 22 through the pipes 73 and 74, and fluid pressure thus enters in the front of the piston 54 and moves the controlling slide valve 38 back to its original position as shown in the drawing. As soon as the slide valve 38 reaches this position, the slot 63 is again brought into register with the port leading to the pipe 62 and fluid pressure enters underneath the piston 59 and 40 cooperates with the spring 61 to again raise the restoring device to its normal position, the space above the piston 59 being again vented to the atmosphere through the pipe 64, passageway 65, and atmospheric port 50.

It will now be understood that as the lever arm 26 is turned upon its pivot, fluid pressure will be admitted to the piston actuating device of the brake applying valve mechanism to actuate the same and apply the 50 brakes unless this is prevented by the controlling valve; and that the operation of this controlling valve is manually initiated and is automatically completed, and its initial movement serves to divert the fluid pressure from the brake applying valve mechanism to the piston mechanism which completes the operation of the controlling valve; and that in its final movement the controlling valve admits pressure fluid to the 65

restoring device which restores the operating valve to its original position, and the restoring device in its final movement restores the controlling valve to its original position and resets the handle 42 and connected parts and thereby shuts off the fluid pressure from the restoring device, which then assumes its original position. It will thus be observed that the operating valve, the controlling valve, and the restoring devices perform 75 their complete operation each time that the movement of the controlling valve is initiated, and hence the engineer can be continually apprised of the condition of the apparatus.

To prevent the engineer from continually holding the handle 42 forward so that the above described operations will automatically take place when the lever arm 26 is actuated, and thus permit him to relax his 80 vigilance, the controlling valve is so constructed that at the beginning of its movement it both opens a port in the main reservoir pressure line and shuts off the steam from the compressor. At this port may be 85 provided a whistle 76, as shown, the port being located in the casing 39 of the controlling valve in such position that it is normally covered by the slide valve 38 but is uncovered at the beginning of the movement of 90 the slide valve and permits the pressure fluid which enters through the pipe 13 to escape through the whistle 76, thereby giving an audible alarm. At the same time the steam pipe 77 for the compressor 78, which compresses the air stored in the main reservoir 95 100 105 110 115 120 125 130 135 140 145 150 155 160 165 170 175 180 185 190 195 198 at the proper times, a lever 88 is provided which is loosely pivoted upon the transverse shaft 85 substantially under the middle line of the locomotive. This lever 88 is provided with a pawl 89 which engages with a ratchet 90 also fixed upon the shaft 85.

Carried by the frame of the locomotive directly over the rear end of the lever 88 is a solenoid 91 provided with a movable core 92, which is secured to the lever 88, as by a transverse pin 93 engaging in an elongated opening in the lever. When the solenoid 91 is energized, it tends to hold the core 92 elevated and partially projecting within the solenoid as shown. When an armature of soft iron is brought in proximity to the core, the core and armature, according to well known principles, tend to approach each other to decrease the reluctance of the magnetic circuit. To draw the core downwardly in accordance with this principle and thereby depress the rear end of the lever 88 and rotate the ratchet 90, the shaft 85 and the valve-actuating wheel 86, I provide at intervals, in substantially the center of the track, armatures 94 of soft iron. These armatures are fixed in the track and are of sufficient length to assure the downward movement of the core and hence the actuation of the brake applying mechanism by each armature as the train passes over the armature at maximum speed. One of these armatures 94 is provided at each signal post, or, in other words, at the entrance to each block, so that the operating valve is actuated at each signal irrespective of the position of the signal. It will, therefore, be noted that unless the engineer operates the controlling valve and prevents the operation of the brakes, the brakes will be applied at each signal, and since he has this positive act to perform at each signal, he is required to stay at his post in order to keep his train going, and since his attention is thus forcibly called to the fact that he is passing the signal, the likelihood of his passing it without observing it is reduced to a minimum. In actual practice the engineer will operate his controlling device each time just before the operating valve is actuated, so that the pressure fluid which passes through the pipe 24, instead of operating the brake applying mechanism, will operate to complete the movement of the controlling valve, whereby the restoring device is actuated and the parts restored to their normal positions.

The train carried parts of the actuating mechanism are preferably inclosed in a casing 95 of brass or other suitable non-magnetic material. The parts are so arranged that, at each actuation of the lever 88, the wheel 86 is rotated the angular distance between two fingers 87. The lever 88 has a bias to the position which it assumes

with its rear end elevated and the core 92 in its uppermost position in the solenoid 91, and, consequently, as soon as it passes over the armature, it rotates back to its normal or non-operative position, the pawl 89 rotating idly over the teeth of the ratchet 90. For the purpose of giving the lever this bias, it is shown as counterweighted, though other suitable means may be employed for this purpose.

In order that a failure of the electromagnet may be a safe failure, I provide means for applying the brakes when the solenoid is on open circuit. For this purpose a second electro-magnet 96 is provided in series with the solenoid 91, as shown in Fig. 1, both being energized by the battery 97. This electro-magnet 96 is arranged in control of an upwardly seating valve 98 which controls the admission of pressure fluid from the pipe 15 through the pipe 99 behind the piston valve 100. This piston valve 100 reciprocates in a cylinder 101 and its stem 102 passes through a stuffing box into the casing 8 of the brake operating valve mechanism and is secured to the end of the valve 7 on the end opposite that to which the stem 21 of the valve 19 is secured. The valve piston 100 is of larger area than is the valve piston 19, and, consequently, when pressure fluid is admitted behind the piston 100, the valve 7 is moved to the left against the pressure behind the piston 19, and the brakes are applied.

The stem 103 of the valve 98 extends upwardly through the valve casing 104, and carries a downwardly seating venting valve 105 on its upper end, and a pivoted armature lever 106 is attached to the top of the venting valve 105 between the pivot and the free end of the armature lever. An armature 107 is mounted on the lever near its free end. The valve casing 104 communicates with the cylinder 101 behind the valve piston 100 through a passageway 108.

It will now appear that, if the magnet 96 is energized, the armature 107 is attracted and the venting valve 105 is raised off its seat and the valve 98 is closed, with the result that pressure fluid is excluded from the space behind the valve piston 100 and this space is vented to the atmosphere. When the magnet 96 is deenergized, however, the armature 107 and connected parts fall by gravity and close the venting valve 105 and open the valve 98, and the valve 7 is moved to the left and the brakes are applied. Thus a rupture in the circuit of the solenoid 91 serves to apply the brakes, and the engineer is at once apprised of the fact that his actuating mechanism for the operating lever is out of order. The armatures 94 are securely spiked in place and the liability of failure of proper operation of the mechanism is reduced to a minimum.

It will be noted that, with each actuation of the wheel 86, a finger 87 is brought up in position to contact with the lever 26, but no finger is left in the path of the lever 26 so as to impede its free return to normal running position. The lever 26 can, therefore, be restored and the brakes be prevented from going on or be released if the lever 88 does not return to its original position. This is important in case the train should stop with the magnet over an armature.

As an additional precaution, I prefer also to provide another tripping or actuation device in safe stopping distance in rear of each signal, which is controlled by the condition of the signal. If an engineer enters a block guarded by a caution signal, since this indicates that the home signal of the block ahead is at danger, he should approach the next signal under control. In order to assure that he will stop before entering the next block if the next signal is still at danger, I provide a tripping or actuating device a safe stopping distance in rear of each signal so associated with the signal actuating mechanism that it is operative if the signal is at danger and is inoperative if the signal is at clear. This mechanism comprises an armature 94' similar to the armature 94, and at each side of the armature 94' an electro-magnet 109 is arranged. As a counterbalance for the lever 88, a transversely extending bar 110 of soft iron is provided on the front end of the lever 88 and adapted to extend across the two track electro-magnets 109 and serve as an armature for these magnets when they are energized. When a locomotive passes this mechanism, the track armature 94' tends to draw the core 92 down and thus apply the brakes, but this application of the brakes is prevented if the track magnets 109 are energized, since the attraction of the two magnets for the armature 94' and bar 110 exceeds that between the core 92 and the track armature 94'.

As shown in Fig. 7, the track magnets 109 are energized through a circuit controlled by mechanism energized in series with the signal controlling mechanism. The signal controlling relay 111, which controls the local signal circuit, is energized in the usual way by the track circuit comprising the battery 112, wire 113, the right rail, wire 114, relay 111, wire 115, relay 119, the left rail and wire 116 back to the battery. When the block is unoccupied and the relay 111 is energized, as shown at station B, the contact finger 117 is attracted and the local signal circuit is completed through the battery 118 and the signal is held at clear. The train T in the block A-B has shunted the relay 111 and the local signal circuit of station A is therefore broken and the signal assumes the danger indication by gravity.

65 In series with the signal controlling re-

lay 111 is the track magnet controlling relay 119 which controls the local circuit for the track magnets 109. This local circuit is energized by the local battery 120 and includes the contact finger 121 controlled by the relay 119. The relay 119 is, therefore, energized and deenergized with the relay 111, and the track magnets 109 are energized when the block ahead is clear and are deenergized when the block ahead is occupied. It sometimes occurs that the signal gets stuck at clear position after the signal actuating mechanism has been deenergized, and under such conditions the brakes will be applied, while otherwise the engineer, on getting the clear signal would proceed into an occupied block.

The positions of the armatures 94' may be indicated by miniature signals along the track, and the engineer might in practice operate his controlling lever 42 as he approaches these armatures and thereby operate the restoring mechanism and prevent the brakes from going on, even when the track relays 109 were deenergized. To obviate this and assure that the engineer cannot thus nullify the operation of the armature 94', another armature 94" which may be termed the resetting armature, is provided immediately behind the armature 94'. This resetting armature 94" will, if not prevented, apply the brakes by attracting the core 92 and the engineer will, therefore, be compelled to operate his controlling lever 42 at this point to prevent his brakes from going on. As previously described, this operation of the controlling lever 42 initiates an operation which results in the operation of the restoring mechanism and finally in the resetting of the valve 38 and the lever 42 back to their original positions by the admission of pressure fluid in front of the piston valve 54. The lever 42 is thus automatically reset and the parts are in position for the brakes to be applied as the core 92 moves over the armature 94', if the track armatures 109 are not energized.

It will now appear that, if the signal which the train is approaching is at danger or should be at danger, the brakes will be applied at a safe stopping distance before the signal is reached and the engineer cannot prevent the application of the brakes by the customary operation of his controlling mechanism.

It is obvious that various modifications may be made in the construction shown in the drawings and above particularly described within the principle and scope of my invention.

I claim:—

1. In a railway traffic-controlling system in combination with a railway track and a vehicle thereon, brake applying mechanism for the vehicle, and automatic actuating

means for the brake applying mechanism comprising a movable magnet carried by the vehicle and operative by its movement to actuate the brake applying mechanism, an armature fixed in the track in position to co-operate with the magnet and cause the magnet to actuate the brake applying mechanism as the vehicle passes the armature, restoring mechanism for the brake applying mechanism, and manually controlled means for operating the restoring mechanism.

2. In a railway traffic-controlling system, in combination with a railway track and a vehicle thereon, brake applying mechanism for the vehicle, and automatic actuating means for the brake applying mechanism comprising a lever operative to actuate the brake applying mechanism, an electro-magnetic member fixed to the lever, an armature fixed in the track in position to co-operate with said member as the vehicle passes the armature and move said member toward the armature and thereby operate the lever to actuate the brake applying mechanism, restoring mechanism for the brake applying mechanism, and manually controlled means for operating the restoring mechanism.

3. In a railway traffic-controlling system, in combination with a railway track and a vehicle thereon, brake applying mechanism for the vehicle, and automatic actuating means for the brake applying mechanism comprising a lever operative to actuate the brake applying mechanism and having a bias to non-operative position, a solenoid carried by the vehicle, a movable core for the solenoid operative by its movement out of the solenoid to move the lever to operative position, an armature fixed in the track in position to co-operate with the core as the vehicle passes the armature and move the core outwardly and thereby operate the lever to actuate the brake applying mechanism, restoring mechanism for the brake applying mechanism, and manually controlled means for operating the restoring mechanism.

4. In a railway traffic-controlling system, in combination with a railway track and a vehicle thereon, brake applying mechanism for the vehicle, and automatic actuating means for the brake applying mechanism comprising a movable electro-magnetic member carried by the vehicle and operative by its movement to actuate the brake applying mechanism, an armature fixed in the track in position to co-operate with the electro-magnetic member and cause the electro-magnetic member to actuate the brake applying mechanism as the vehicle passes the armature, and means operative to apply the brakes when the electro-magnetic member is deenergized.

5. In a railway traffic-controlling system, in combination with a railway track and a

vehicle thereon, brake applying mechanism for the vehicle, automatic actuating means for the brake applying mechanism comprising a lever operative to actuate the brake applying mechanism, an electro-magnetic member fixed to the lever and a normally closed electric circuit therefor, an armature fixed to the track in position to co-operate with the electro-magnetic member as the vehicle passes the armature and move said member toward the armature and thereby operate the lever to actuate the brake applying mechanism, and means operative to apply the brakes when said electric circuit is open.

6. In a railway traffic-controlling system, in combination with a railway track and a vehicle thereon, brake applying mechanism for the vehicle, automatic actuating means for the brake applying mechanism comprising a lever operative to actuate the brake applying mechanism and having a bias to non-operative position, an electro-magnetic member fixed to the lever and a normally closed electric circuit therefor, an armature fixed to the track in position to co-operate with the electro-magnetic member as the vehicle passes the armature and move said member toward the armature and thereby operate the lever to actuate the brake applying mechanism, and an electro-translative device arranged in series in the energizing circuit of the electro-magnetic member and operatively related to the brake applying mechanism and operative in open circuit to actuate the brake applying mechanism and apply the brakes.

7. In a railway traffic-controlling system, in combination with a railway track, a vehicle thereon and a stationary signal apparatus along the track; brake applying mechanism for the vehicle, and automatic actuating means for the brake applying mechanism comprising a lever operative to actuate the brake applying mechanism and having a bias to non-operative position, an electro-magnetic member fixed to the lever, an armature fixed in the track in position to co-operate with said member as the vehicle passes the armature and move said member toward the armature and thereby operate the lever to actuate the brake applying mechanism, means controlled by the signal apparatus for preventing the lever from moving to operative position, restoring mechanism for the brake applying mechanism, and manually controlled means for operating the restoring mechanism.

8. In a railway traffic-controlling system, in combination with a railway track, a vehicle thereon, electro-translative signal-actuating mechanism along the track and a track circuit in control thereof, brake applying mechanism for the vehicle and automatic engaging means for the brake applying mechanism comprising a pivoted lever oper-

- ative to actuate the brake applying mechanism and having a bias to non-operative position, a train electro-magnetic member fixed to the lever on one side of the pivot, a track armature fixed in the track in position to coöperate with said member as the vehicle passes the track armature and move said member toward the track armature and thereby operate the lever to actuate the 5 brake applying mechanism, an armature carried by the lever on the opposite side of the pivot, a track electro-magnet arranged at the side of the track armature and operative when energized to coöperate with the armature carried by the lever and hold the lever against movement to operative position under the influence of the track armature, and an electric circuit for the track electro-magnet controlled by the signal-actuating electro-translative mechanism, the circuit being closed 10 when the electro-translative mechanism is energized and being open when the electro-translative mechanism is deenergized.
11. In a railway traffic-controlling system, in combination with a railway track and a vehicle thereon, brake applying mechanism for the vehicle including a train pipe and a source of pressure fluid, a brake applying valve mechanism controlled by the pressure fluid and operative to reduce the pressure in the train pipe, an operating valve arranged to admit pressure fluid to the brake applying valve mechanism to operate the same, a lever operative to actuate the operating valve and having a bias to non-operative position, an electro-magnetic member fixed to the lever, an armature fixed in the track in position to coöperate with said member as the vehicle passes the armature and move said member toward the armature and thereby operate the lever to actuate the 15 brake applying mechanism, means operative to apply the brakes when the electro-magnetic member is deenergized, and means controlled by the signal apparatus for preventing the lever from moving to operative position.
12. In a railway traffic-controlling system, in combination with a railway track, a vehicle thereon, electro-translative signal-actuating mechanism along the track and a track 20 circuit in control thereof; brake applying mechanism for the vehicle and automatic actuating means for the brake applying mechanism comprising a pivoted lever operative to actuate the brake applying mechanism and having a bias to non-operative position, a train electro-magnetic member fixed to the lever on one side of the pivot, a track armature fixed in the track in position to coöperate with said member as the vehicle 25 passes the track armature and move said member toward the track armature and thereby operate the lever to actuate the brake applying mechanism, means operative to apply the brakes when said member is deenergized, an armature carried by the 30 lever on the opposite side of the pivot, a track electro-magnet arranged at the side of the track armature and operative when energized to coöperate with the armature carried by the lever and hold the lever against movement to operative position under the influence of the track armature, and an electric circuit for the track electro-magnet controlled by the signal-actuating electro-translative mechanism, the circuit being closed 35 when the electro-translative mechanism is energized and being open when the electro-translative mechanism is deenergized.
13. In a railway traffic-controlling system, in combination with a railway track and a vehicle thereon, brake applying mechanism for the vehicle including a train pipe and a source of pressure fluid, a brake applying valve mechanism controlled by the pressure fluid and operative to reduce the pressure in the train pipe, an operating valve arranged to admit pressure fluid to the brake applying valve mechanism to operate the same, a rotary member operative by its rotation to actuate the operating valve, a lever pivoted co-axially with the rotary member and having pawl and ratchet connection therewith, an electro-magnetic member fixed to the lever, and an armature fixed in the track in position to coöperate with said member as the vehicle passes the armature and move said member toward the armature and thereby operate the lever to rotate the 40 rotary member.
14. In a railway traffic-controlling system, in combination with a railway track and a vehicle thereon, brake applying mechanism for the vehicle including a train pipe and a source of pressure fluid, a brake applying valve mechanism controlled by the pressure fluid and operative to reduce the pressure in the train pipe, an operating valve arranged to admit pressure fluid to the brake applying valve mechanism to operate the 45 same, a pivoted lever operative to actuate the operating valve, a rotary member operative by its rotation to actuate the operating valve, a lever pivoted co-axially with the rotary member and having pawl and ratchet connection therewith, an electro-magnetic member fixed to the lever, and an armature fixed in the track in position to coöperate with said member as the vehicle passes the armature and move said member toward the armature and thereby operate the lever to rotate the 50 rotary member.
15. In a railway traffic-controlling system, in combination with a railway track and a vehicle thereon, brake applying mechanism for the vehicle including a train pipe and a source of pressure fluid, a brake applying valve mechanism controlled by the pressure fluid and operative to reduce the pressure in the train pipe, an operating valve arranged to admit pressure fluid to the brake applying valve mechanism to operate the 55 same, a pivoted lever operative to actuate the operating valve, a rotary member operative by its rotation to actuate the operating valve, a lever pivoted co-axially with the rotary member and having pawl and ratchet connection therewith, an electro-magnetic member fixed to the lever, and an armature fixed in the track in position to coöperate with said member as the vehicle passes the armature and move said member toward the armature and thereby operate the lever to rotate the 60 rotary member.
16. In a railway traffic-controlling system, in combination with a railway track and a vehicle thereon, brake applying mechanism for the vehicle including a train pipe and a source of pressure fluid, a brake applying valve mechanism controlled by the pressure fluid and operative to reduce the pressure in the train pipe, an operating valve arranged to admit pressure fluid to the brake applying valve mechanism to operate the 65 same, a pivoted lever operative to actuate the operating valve, a rotary member operative by its rotation to actuate the operating valve, a lever pivoted co-axially with the rotary member and having pawl and ratchet connection therewith, an electro-magnetic member fixed to the lever, and an armature fixed in the track in position to coöperate with said member as the vehicle passes the armature and move said member toward the armature and thereby operate the lever to rotate the 70 rotary member.

- same, a lever operative to actuate the operating valve and having a bias to non-operative position, an electro-magnetic member fixed to the lever, an armature fixed in the track in position to coöperate with said member as the vehicle passes the armature and move said member toward the armature and thereby operate the lever to actuate the operative valve, and means operative to 10 operate the brake applying valve mechanism when the electro-magnetic member is de-energized.
14. In a railway traffic-controlling system, in combination with a railway track and a vehicle thereon, brake applying mechanism for the vehicle including a train pipe and a source of pressure fluid, a brake applying valve mechanism controlled by the pressure fluid and operative to reduce the pressure in the train pipe, an operating valve arranged to admit pressure fluid to the brake applying valve mechanism to operate the same, a movable magnetized member carried by the vehicle and operative by its movement to 20 open the operating valve, an armature fixed in the track in position to coöperate with said member and cause said member to move and actuate the operating valve as the vehicle passes the armature, restoring mechanism operative to restore the operating valve, manually controlled means for operating the restoring mechanism, restoring mechanism for the manually controlled means, and means in the track in advance 30 of the armature compelling the exercise of manual control for operating the restoring mechanisms.
15. In a railway traffic-controlling system, in combination with a railway track and a vehicle thereon, brake applying mechanism for the vehicle including a train pipe and a source of pressure fluid, a brake applying valve mechanism controlled by the pressure fluid and operative to reduce the pressure in the train pipe, an operating valve arranged to admit pressure fluid to the brake applying valve mechanism to operate the same, a movable magnetized member carried by the vehicle and operative by its movement 40 to open the operating valve, restoring mechanism controlled by the pressure fluid and operative to restore the operating valve to closed position, manually controlled means for diverting pressure fluid from the brake applying mechanism to the restoring mechanism, automatic resetting means for the manually controlled means, and two armatures fixed in the track in close succession, each armature being arranged to coöperate 50 with the magnetized member and cause said member to move and actuate the operating valve as the vehicle passes the respective armatures, whereby the manually controlled means will be reset by reason of the manual 60 control compelled by the first armature and

the pressure fluid will operate the brake applying valve mechanism as the operating valve is actuated by the second armature.

16. In a railway traffic-controlling system, in combination with a railway track, a vehicle thereon and a stationary signal apparatus along the track; brake applying mechanism for the vehicle including a train pipe and a source of pressure fluid, a brake applying valve mechanism controlled by the pressure fluid and operative to reduce the pressure in the train pipe, an operating valve arranged to admit pressure fluid to the brake applying valve mechanism to operate the same, a movable magnetized member carried by the vehicle and operative by its movement to open the operating valve, an armature fixed in the track in position to coöperate with said member and cause said member to move and actuate the operating valve as the vehicle passes the armature, restoring mechanism operative to restore the operating valve, manually controlled means for operating the restoring mechanism, restoring mechanism for the manually controlled means, means in the track in advance of the armature compelling the exercise of manual control for operating the restoring mechanisms, and means controlled by the signal apparatus for preventing the actuation of the operating valve by the track armature. 70
17. In a railway traffic-controlling system, in combination with a railway track, a vehicle thereon and a stationary signal apparatus along the track; brake applying mechanism for the vehicle including a train pipe and a source of pressure fluid, a brake applying valve mechanism controlled by the pressure fluid and operative to reduce the pressure in the train pipe, an operating valve arranged to admit pressure fluid to the brake applying valve mechanism to operate the same, a movable magnetized member carried by the vehicle and operative by its movement to open the operating valve, restoring mechanism controlled by the pressure fluid and operative to restore the operating valve to closed position, manually controlled means for diverting pressure fluid from the brake applying mechanism to the restoring mechanism, automatic resetting means for the manually controlled means, two armatures fixed in the track in close succession, each armature being arranged to coöperate with the magnetized member and cause said member to move and actuate the operating valve as the vehicle passes the respective armatures, whereby the manually controlled means will be reset by reason of the manual control compelled by the first armature and the pressure fluid will operate the brake applying valve mechanism as the operating valve is actuated by the second armature, and means disposed at the side 80

- of the second armature and controlled by the signal apparatus for preventing the actuation of the operating valve by the second armature.
- 5 18. In a railway traffic-controlling system, in combination with a railway track, a vehicle thereon, an electro-translative signal mechanism along the track and a track circuit in control thereof; brake applying mechanism for the vehicle including a train pipe and a source of pressure fluid, a brake applying valve mechanism controlled by the pressure fluid and operative to reduce the pressure in the train pipe, an 10 operating valve arranged to admit pressure fluid to the brake applying valve mechanism to operate the same, a pivoted lever operative to actuate the operating valve and having a bias to non-operative position, a 15 train electro-magnetic member fixed to the lever on one side of the pivot, an armature carried by the lever on the opposite side of the pivot, restoring mechanism controlled by the pressure fluid and operative to restore the operating valve to closed position, manually 20 controlled means for diverting pressure fluid from the brake applying mechanism to the restoring mechanism, automatic resetting means for the manually controlled 25 means, two armatures fixed in the track in close succession, each armature being arranged to coöperate with the electro-magnetic member and cause said member to move and actuate the operating valve as the 30 vehicle passes the respective armatures, whereby the manually controlled means will be reset by reason of the manual control 35 compelled by the first armature and the pressure fluid will operate the brake applying valve mechanism as the operating valve is actuated by the second armature, a track 40 electro-magnet arranged at the side of the second armature and operative when energized to coöperate with the armature carried by the lever and hold the lever against 45 movement to operative position under the influence of the track armature, and an electric circuit for the track electro-magnet controlled by the signal actuating electro- 50 translative means, the circuit being closed when the electro-translative means is energized and being open when the electro-translative mechanism is deenergized.
- 45 19. In a railway traffic-controlling system, in combination with a railway track and a vehicle thereon, brake applying mechanism for the vehicle including a train pipe and a source of pressure fluid, a brake applying valve mechanism controlled by the 55 pressure fluid and operative to reduce the pressure in the train pipe, an operating valve arranged to admit pressure fluid to the brake applying valve mechanism to operate the same, a movable electro-magnetic member carried by the vehicle and operative by 60 its movement to open the operating valve, means operative to apply the brakes when the electro-magnetic member is deenergized, an armature fixed in the track in position to coöperate with said member to cause said member to move and actuate the operating valve as the vehicle passes the armature, restoring mechanism operative to restore the operating valve, manually controlled means for operating the restoring mechanism, resetting means for the manually controlled means, and means in the track in advance of the armature compelling manual control for operating the resetting means.
- 65 20. In a railway traffic-controlling system, in combination with a railway track and a vehicle thereon, brake applying mechanism for the vehicle including a train pipe and a source of pressure fluid, a brake applying valve mechanism controlled by the pressure fluid and operative to reduce the pressure in the train pipe, an operating valve arranged to admit pressure fluid to the brake applying valve mechanism to operate the same, a movable electro-magnetic member carried by the vehicle and operative by its movement to open the operating valve, an electro-translative device arranged in series within the energizing circuit of the electro-magnetic member and operatively related to the brake applying valve mechanism and operative in open circuit to admit pressure fluid to the brake applying valve mechanism and apply the brakes, an armature fixed in the track in position to coöperate with the electro-magnetic member to cause the said member to move and actuate the operating valve as the vehicle passes the armature, restoring mechanism operative to restore the operating valve, manually controlled means for operating the restoring mechanism, resetting means for the manually controlled means, and means in the track in advance of the armature compelling manual control for operating the resetting means.
- 70 21. In a railway traffic-controlling system, in combination with a railway track and a vehicle thereon, brake applying mechanism for the vehicle including a train pipe and a source of pressure fluid, a brake applying valve mechanism controlled by the pressure fluid and operative to reduce the pressure in the train pipe, an operating valve arranged to admit pressure fluid to the brake applying valve mechanism to operate the same, a movable electro-magnetic member carried by the vehicle and operative by its movement to open the operating valve, means operative to apply the brakes when the electro-magnetic member is deenergized, restoring mechanism controlled by the pressure fluid and operative to restore the operating valve to closed position, manually controlled means for diverting pressure 75

fluid from the brake applying valve mechanism to the restoring mechanism, automatic resetting means for the manually controlled means, and two armatures fixed in 5 the track in close succession, each armature being arranged to coöperate with the electro-magnetic member and cause said member to move and actuate the operating valve as the vehicle passes the respective 10 armatures, whereby the manually controlled means will be reset by reason of the manual control compelled by the first armature and the pressure fluid will operate the brake applying valve mechanism as the operating 15 valve is actuated by the second armature.

22. In a railway traffic-controlling system, in combination with a railway track and a vehicle thereon, brake applying mechanism for the vehicle, and automatic actuating means for the brake applying mechanism comprising a movable magnetic

member carried by the vehicle and operative by its movement to actuate the brake applying mechanism, a stationary magnetic member carried by the vehicle in control of 25 the movable magnetic member, a magnetically-acting member fixed in the track in position to counteract the magnetic action of the stationary vehicle-carried magnetic member and move the movable magnetic member 30 for actuating the brake applying mechanism as the vehicle passes the track member, restoring mechanism for the brake applying mechanism, and manually controlled means for operating the restoring mechanism. 35

In testimony whereof I have affixed my signature in presence of two witnesses.

JOHN FOURNIA.
